(57) **CLAIM**

The ornamental design for a display screen with graphical user interface, as shown and described.

DESCRIPTION

The patent file contains at least one drawing executed in color. Copies of this patent with color drawing(s) will be provided by the Patent and Trademark Office upon request and payment of the necessary fee.

The sole FIGURE is a front elevational view of a display screen with graphical user interface showing our new design.

The broken lines illustrate a display screen and form no part of the claimed design.
